(57) **CLAIM**

The ornamental design for a fishing lure frame, as shown and described.

DESCRIPTION

FIG. 1 is a front elevational view of the fishing lure frame. FIG. 2 is a rear elevational view of the fishing lure frame. FIG. 3 is a left side elevational view of the fishing lure frame.

FIG. 4 is a right side elevational view of the fishing lure frame.

FIG. 5 is a perspective view of the fishing lure frame; and, FIG. 6 is a perspective view of the fishing lure frame of FIGS. 1-5 but shown with an additional non-claimed, removable, interchangeable fishing lure insert.

The broken lines showing the hook, the fishing lure insert, and the fishing line connector are included for the purpose of illustrating environmental elements only and form no part of the claimed design.
